UNITED STATES PATENT OFFICE

2,492,118

RETRACTING TYPE THEATER CHAIR

John J. Roman, Grand Rapids, Mich., assignor to American Seating Company, Grand Rapids, Mich., a corporation of New Jersey

Application July 27, 1946, Serial No. 686,674

8 Claims. (Cl. 155—116)

1

The present invention relates to chairs and more particularly to chairs of the retracting type for installation in theaters, auditoriums and the like.

The primary objects of the invention are to provide an improved chair of the retracting type wherein the chair occupant may move rearwardly in a sitting position in order to permit other theater patrons to pass in front of him; to provide such a chair which is of simple construction and which comprises few moving parts; to provide such a chair which may be easily and comfortably retracted and returned to forward position by the chair occupant; and in general to provide a retracting chair which is efficient in operation, reasonably economical in manufacture, and attractive in appearance.

An illustrative embodiment of the invention is shown in the accompanying drawings, wherein:

Figure 1 is a perspective view of a retracting chair in its forward position of occupancy;

Figure 2 is a sectional view of the same taken on line 2—2 of Figure 3;

Figure 3 is a fragmentary front elevational view showing the right hand side of the chair;

Figure 4 is a perspective view similar to Figure 1 and showing the chair in its rearwardly retracted position; and

Figure 5 is a sectional view similar to Figure 2 and showing the parts of the chair in their rearwardly moved positions.

Referring now in detail to these drawings, the retracting chair there shown is mounted upon a frame which comprises spaced, upright standards 10 which may be secured to the floor in any suitable manner and which may if desired be rigidly connected by a suitable cross-tie (not shown). As here shown, the only connections between the standards are the chair parts hereinafter described and the floor upon which the standards are installed, and the word "frame" as herein used is intended to include spaced standards as well as a unitary structure.

The chair proper generally comprises a seat and back assembly in which the chair seat 11 and the chair back 12 are pivotally connected for relative movement. The chair back 12 is mounted at its opposite sides on spaced back carriers 13 as by means of rivets 14. The chair seat 11 is mounted on spaced seat carriers 15 at opposite sides thereof by means of brackets 16 secured to the seat 11 by rivets 17 and which brackets 16 are pivotally connected at 18 to the seat carriers 15.

The rearward ends of the seat carriers 15 are pivotally connected at 19 to the lower, rearward

2

ends or corners of the adjacent back carriers 13 thus connecting the seat and back in pivoted assembly.

The seat carriers 15 and back carriers 13 are mounted on the standards 10 by means of rear depending links 20 having their upper ends pivotally connected to the standards and their lower ends pivotally connected to the seat carriers and back carriers at their pivotal connection 19. The seat and back assembly is thus supported in the rear for forward and rearward movements by the swingable depending links 20.

Intermediate depending links 21 support the back carriers 13 and back 12 forwardly of the rear links 20, said links 21 having their upper ends pivotally connected to the standards 10 and their lower ends pivotally connected to the forward parts of the back carriers 13. These swingable intermediate links 21 are of greater length than the rear links 20, and by this arrangement as the chair back is moved rearwardly it is also tilted to a near-vertical position thus to minimize the space required to the rear of the chair for retraction.

25 The forward portions of the seat carriers 15 and of the seat 11 are forwardly-rearwardly movably supported by swingable, upstanding front supporting levers 22 having their lower ends pivotally connected to the standards 10 and their upper ends pivotally connected to the upper forward corners of the seat carriers 15. These front levers 22 are preferably connected by a cross-tie or strut 23 which adds to the stability of the structure.

35 It will be seen that as the chair is retracted by the occupant thereof, the seat moves rearwardly in a substantially straight path while the back moves rearwardly and is simultaneously turned to a near vertical position as seen in Figure 5. This rearward retracting movement is stopped by contact of the front levers 22 with stops or bumpers 24 on the standards 11. Forward, returning movement of the chair from its position shown in Figure 5 to its position shown in Figure 1 is similarly stopped by contact of the front levers 22 with stops 25 on the standards.

40 It will be seen that the chair seat 11 may be folded upwardly to facilitate sweeping under the chair independently of its retracting and returning movements, by reason of its pivotal mountings on the seat carriers 15. The seat is supported in its lowered, substantially horizontal position for occupancy by cooperating stops 26 on the brackets 16 and 27 on the seat carriers 15.

45 While but one specific embodiment of the in-

vention has been herein shown and described, it will be understood that certain details may be altered or omitted without departing from the spirit of the invention as the same is defined by the following claims.

I claim:

1. In a chair, a frame, a seat and back assembly wherein the seat and back are pivotally connected for relative movement, links swingably depending from the frame and having their lower ends pivotally connected to the rearward part of the seat and back assembly, other links swingably depending from the frame and having their lower ends pivotally connected to the back forwardly of the first-mentioned links, and means mounted on the frame for supporting the seat forwardly of the first-mentioned links.

2. In a chair, a frame, a seat and back assembly wherein the seat and back are pivotally connected for relative movement, links swingably depending from the frame and having their lower ends pivotally connected to the rearward part of the seat and back assembly, other links swingably depending from the frame and having their lower ends pivotally connected to the back forwardly of the first-mentioned links, and levers swingably upstanding from the frame and having their upper ends pivotally connected to the seat forwardly of the first-mentioned links.

3. In a chair, a frame, a seat and back assembly wherein the seat and back are pivotally connected for relative movement, links swingably depending from the frame and having their lower ends pivotally connected to the rearward part of the seat and back assembly, other links of greater length than the first-mentioned links swingably depending from the frame and having their lower ends pivotally connected to the back forwardly of the first-mentioned links, and means mounted on the frame for supporting the seat forwardly of the first-mentioned links.

4. In a chair, a frame, a seat and back assembly wherein the seat and back are pivotally connected for relative movement, links swingably depending from the frame and having their lower ends pivotally connected to the rearward part of the seat and back assembly, other links of greater length than the first-mentioned links swingably depending from the frame and having their lower ends pivotally connected to the back forwardly of the first-mentioned links, and levers swingably upstanding from the frame and having their upper ends pivotally connected to the seat forwardly of the first-mentioned links.

5. In a chair, a frame, spaced seat carriers and back carriers arranged with a pivotally connected seat carrier and back carrier at each opposite side of the frame, a seat mounted on the seat carriers, a back mounted on the back carriers, links swingably depending from opposite sides of the frame and pivotally connected at their lower ends to the rearward parts of the seat carriers and to the lower rearward parts of the back carriers, other links swingably depending from opposite sides of the frame and pivotally connected at their lower ends to the forward parts of the back carriers, and means mounted on the frame for supporting the forward parts of the seat carriers.

6. In a chair, a frame, spaced seat carriers and back carriers arranged with a pivotally connected seat carrier and back carrier at each opposite side of the frame, a seat mounted on the

5 seat carriers, a back mounted on the back carriers, links swingably depending from opposite sides of the frame and pivotally connected at their lower ends to the rearward parts of the seat carriers and to the lower rearward parts of the back carriers, other links swingably depending from opposite sides of the frame and pivotally connected at their lower ends to the forward parts of the back carriers, and levers swingably upstanding from the frame and having their upper ends pivotally connected to the forward parts of the seat carriers.

7. In a chair, spaced chair-supporting standards, spaced seat carriers and spaced back carriers associated with said standards and having pivotal connections at their rearward ends, a seat mounted on the seat carriers, a back mounted on the back carriers, and means for mounting the seat carriers on the standards for forward and rearward movements and the back carriers on the standards for forward and rearward movements and tilting movement about a horizontal axis, said means comprising rear links having their upper ends pivotally connected to the standards and their lower ends pivotally connected to the seat carriers and the back carriers at their aforesaid pivotal connections, intermediate links having their upper ends pivotally connected to the standards and their lower ends pivotally connected to the forward ends of the back carriers, and front levers having their lower ends pivotally connected to the standards and their upper ends pivotally connected to the forward ends of the seat carriers.

8. In a chair, spaced chair-supporting standards, spaced seat carriers and spaced back carriers associated with said standards and having pivotal connections at their rearward ends, a seat mounted on the seat carriers turnably about a horizontal axis, cooperating stop means on the seat and the seat carriers for supporting the forward portion of the seat when the same is in a substantially horizontal position for occupancy, a back mounted on the back carriers, and means for mounting the seat carriers on the standards for forward and rearward movements and the back carriers on the standards for forward and rearward movements and tilting movement about a horizontal axis, said means comprising rear links having their upper ends pivotally connected to the standards and their lower ends pivotally connected to the seat carriers and the back carriers at their aforesaid pivotal connections, intermediate links having their upper ends pivotally connected to the standards and their lower ends pivotally connected to the forward ends of the back carriers, and front levers having their lower ends pivotally connected to the standards and their upper ends pivotally connected to the forward ends of the seat carriers.

JOHN J. ROMAN.
